UNITED STATES PATENT OFFICE.

FREEMAN N. YOUNG AND FRANCIS E. THOMPSON, OF ARLINGTON,
MASSACHUSETTS.

DESIGN FOR A REFRIGERATOR.

SPECIFICATION forming part of Design No. 31,417, dated August 15, 1899.

Application filed June 28, 1899. Serial No. 722,198. Term of patent 14 years.

To all whom it may concern:

Be it known that we, FREEMAN N. YOUNG and FRANCIS E. THOMPSON, citizens of the United States, residing at Arlington, in the county of Middlesex and State of Massachusetts, have invented a certain new and original Design for Refrigerators, of which the following is a full, clear, and exact description.

Our design for a refrigerator is illustrated in the accompanying drawings, in which—

Figure 1 is a perspective view of the device, and Fig. 2 is a horizontal section thereof.

The leading or material feature of the design consists of the bottle A, having an elongated body and a short neck a, and in its face, above the middle, a rectangular figure b c d e,

crossed by a center vertical line f g and representing a pair of doors. The representation of a pair of hinges i i for each door is also a part of the design. The horizontal section 20 of the device is circular.

Having described our design, we claim—
The design for a refrigerator as herein described and shown.

In witness whereof we subscribe our signatures in presence of two witnesses.

FREEMAN N. YOUNG.
FRANCIS E. THOMPSON.

Witnesses:

W. M. A. ROSENBAUM,
FRANK S. OBER.
